CENTRALIZED TRAFFIC CONTROLLING
SYSTEM FOR RAILROADSWinfred T. Powell, Rochester, N. Y., assignor to
General Railway Signal Company, Rochester,
N. Y.

Application July 29, 1933, Serial No. 682,829

14 Claims. (Cl. 177—380)

This invention relates to centralized traffic controlling systems for railroads and it more particularly pertains to means employed for interrelating the operation of a plurality of traffic controlling devices with the operation of the communication part of such a system.

In that type of centralized traffic controlling system where a communication system of the station selective type is employed, control impulses are transmitted from the central control office to the several field stations during separate operating cycles. Similarly, indication impulses are transmitted to the control office in accordance with the positions of the various traffic controlling devices at the several field stations and these indication impulses are transmitted to the control office, one station for each operating cycle. Since the present invention is directed to the transmission of controls from the control office to the various field stations, the indication portion of the centralized traffic controlling system is not disclosed.

The invention more specifically embodies means for associating a plurality of stored start conditions with the communication system in the order in which these start conditions are stored. For example, the operator in the control office may operate the three keys or starting buttons 1SB, 2SB and 3SB, shown in Fig. 1, in any desired order and in accordance with the present invention the associated stations will be selected in accordance with the order of operation of these buttons. In former systems of this type the starting buttons associated with the various field stations were actively associated with the communication system in the order of their location or connection in the code determining relay bank.

In view of the above and other considerations, the present invention proposes to provide means whereby the effect of several changed conditions in the control office, as determined by the operation of several starting buttons, may be suitably stored with the storing means becoming actively associated with the communication system, one at a time, and in the exact order of operation of the starting buttons.

Other objects, purposes and characteristic features of the present invention will be in part obvious from the accompanying drawings and in part pointed out as the description of the invention progresses.

In describing the invention in detail reference will be made to the accompanying drawings, in which:

Fig. 1 illustrates three keys or starting buttons and the associated relays which cooperate in associating these keys with the communication system in the order of operation.

Fig. 2 illustrates the manner in which the polar impulses are selectively applied to the communication line circuit as determined by the particular code determining relay which associates the line circuit with the synchronous stepping relay bank by way of the code jumpers and lever devices.

A centralized traffic controlling system organized as contemplated in accordance with the present invention is considered to comprise a control office located at a convenient point and a plurality of field stations located throughout the territory under the control of the operator. The communication system connecting the control office with these field stations may be of any suitable type, but for convenience in describing the present invention, it is assumed that such a communication system is of the station selective duplex coded type as disclosed, for example, in the pending application of T. J. Judge, et al., Ser. No. 640,062 filed October 28, 1932, corresponding to British Patent 419,399. It is to be understood, however, that the specific form of a communication system is not essential to the functioning of the means embodying the present invention, but rather the means embodying the present invention may be considered as an adjunct to any communication system.

In the communication system contemplated, as used in connection with the present invention, a series stepping or control line circuit connects the control office with the several field stations and receives current impulses from a suitable source of energy located in the control office. This line circuit is indicated in the lower right-hand portion of Fig. 2 by reference characters 10 and 12 which correspond to like reference characters in the above-mentioned prior application Ser. No. 640,062. A series message or indication line circuit likewise connects the control office with the various field stations but, as above mentioned, this portion of the system has been omitted from the present disclosure.

Slow acting relays SA and 2SA of Fig. 2 correspond to relays SA and 2SA of the above-mentioned prior application, and it will be understood that these relays are used to define the bounds of an operating cycle, that is, they are picked up at the beginning of a cycle and dropped at the end of the cycle.

Stepping relays 1V, 2V, and 3V, as well as control cycle relay C, correspond to similar relays in the above-mentioned prior application. Likewise, line relay F, impulse relay EP, positive code determining relay PC and negative code determining relay NC, with their associated contacts, correspond to similar relays and contacts in the above-mentioned prior application.

Starting buttons or keys 1SB, 2SB and 3SB are provided for the purpose of initiating the communication system into cycles of operations for selecting corresponding field stations. Change relays 1CH¹, 1CH² and 1CH³ are associated with starting button 1SB, these relays being selectively operated in accordance with the operation of the associated starting button and in accordance with the sequence of operation of this button. In other words, if when the communication system is in its normal-at-rest condition, starting button 1SB is actuated before any of the other starting buttons, relay 1CH¹ will be picked up and stuck up. If button 1SB is the second button actuated in a rapid sequence of operations, following the actuation of one of the other starting buttons, then relay 1CH² will be picked up and stuck up. If button 1SB is the third button operated in the sequence of rapid actuations of the starting buttons following the actuation of two of the other starting buttons, then relay 1CH³ will be picked up and stuck up. Similarly, if button 1SB is actuated three times in succession, relays 1CH¹, 1CH² and 1CH³ will be picked up in rotation and as will be later described the communication system will select the station associated with button 1SB three times in succession.

Change relays 2CH¹, 2CH² and 2CH³ are associated with starting button 2SB and these relays are picked up and stuck up as determined by the sequence in which button 2SB is actuated. For example, if button 2SB is the first one actuated with the system at rest, then relay 2CH¹ is picked up and stuck up. If button 2SB is actuated second in turn then relay 2CH² is picked up and stuck up. If button 2SB is actuated third in turn then relay 2CH³ is picked up and stuck up.

Relays 3CH¹, 3CH² and 3CH³ are selectively actuated in the order of actuation of button 3SB in the same manner as described for the other two buttons. It will be understood that a system of larger capacity than that indicated in Fig. 1 will make use of the same principle of operation of the added buttons and change relays. For each starting button and associated station added to the system a set of change relays is provided, the number of which equals the number of total starting buttons. This means that for each starting button added an additional change relay is added to each group shown in Fig. 1.

Sequence determining relays 1SD, 2SD and 3SD are common to all change relays and are for the purpose of selecting the particular relay associated with a particular starting button as determined by the sequence in which that starting button is actuated. With the system in its normal-at-rest condition, relays 1SD, 2SD and 3SD are deenergized so that the first change relay of each series is selected for operation when an associated starting button is actuated. After this first actuation relay 1SD picks up and extends the selecting circuit to the second change relay of all the groups, so that the next starting button actuated picks up the second change

relay in the associated group. After this second operation relay 2SD is picked up and the third change relays of each group are selected, so that the actuation of the next or third starting button picks up the third change relay of the associated group. This order of operation is followed for as many steps as required as determined by the capacity of the system.

Code determining relays 1CD, 2CD and 3CD correspond to similarly characterized relays in the above-mentioned prior application. These relays are picked up only one at a time during a cycle of operations for determining the character of the impulses applied to the communication circuit for selecting the required station and circuits for conditioning the control devices as determined by the position of the control levers (such as levers 1SML, 2SML and 3SML) associated with the particular code determining relay which is picked up.

A set of code jumpers, such as 40, 55 and 58, corresponding to similar jumpers in the above-mentioned application, select the polarity determining relays PC and NC in different combinations, as determined by code determining relay 1CD being picked up during an operating cycle. Each code determining relay has a corresponding set of code jumpers connected in different combinations, as shown in Fig. 2. Contacts 62, 13 and 32 of relays 1CD, 2CD and 3CD, as well as any other necessary contacts on these relays, selectively operate the polarity determining relays PC and NC as determined by the positions of various lever devices selected by these contacts.

The impulses applied to the control line circuit are governed by relays PC and NC, the line circuit being energized by control battery CB. The interruptions of the energized line are provided by impulse relay EP picking up its back contact 52, all of which is completely disclosed and thoroughly discussed in the above-mentioned prior application Ser. No. 640,062.

Instead of showing the actual connections to the terminals of suitable sources of potential, symbols have been employed to represent such terminals. The symbols (+) and (-) designate the opposite terminals of a suitable source of potential and the circuits with which these symbols are employed always have current flowing in the same direction.

It is believed that the operation and usefulness of the present invention will be best understood by further description being set forth from the standpoint of operation.

OPERATION

Normal conditions

With the system normally-at-rest all of the relays indicated in Fig. 1 and Fig. 2 are in their deenergized conditions. In order that the communication system may be initiated into operation from the control office, the upper windings of relays 1CH¹, 2CH¹ and 3CH¹ have minus potential applied thereto so that the actuation of any one of the starting buttons will pick up the corresponding one of these first change relays of each group.

Manual starting

With the system in a condition of rest, or period of blank, it may be manually initiated into a cycle of operations for the transmission of controls to any desired station. Whenever such a cycle of operation is desired the opera-

tor first positions the control levers of that particular station with which he desires to connect and then actuates the corresponding starting button.

5 Although the operator may position the levers and then actuate the starting buttons simultaneously or in rapid succession, suitable means are provided so that the code call of only one station is transmitted during any one particular 10 cycle of operations and this particular station will be the one which corresponds to the first button actuated. If several buttons are simultaneously actuated then, due to the (+) connections starting at button 1SB and extending 15 in series to the other starting buttons through back contacts, only button 1SB is effective. In other words, it is necessary to operate the starting buttons in a sequential order restoring one before the next is actuated in order to sequentially store the conditions requiring the selection 20 of more than one station.

This feature is provided by the interlocking arrangement of the sequence determining relays and the change relays. The sequence between 25 control operations following the actuation of a number of starting buttons is more conveniently discussed by assuming the actuation of the three buttons illustrated in a particular order or sequence. It will be assumed that the 30 three buttons are operated in order 3, 1, 2. The system, will, therefore, record this order of operations and transmit to stations 3, 1 and 2 in rotation.

The actuation of button 3SB closes a circuit 35 for picking up relay 3CH¹ extending from (+), back contact 3 of button 1SB, back contact 7 of button 2SB, front contact 15 of button 3SB, upper winding of relay 3CH¹, back contact 10 of relay 1SD, back contact 11 of relay 2SD and back contact 12 of relay 3SD to (-). Relay 3CH¹ closes a stick circuit for itself extending 40 from (+), front contact 63 and lower winding of relay 3CH¹ and the lower winding of relay 1SD to (-). Although the current which energizes and sticks relay 3CH¹ by way of its lower winding comes through the lower winding of relay 1SD, this latter relay is not picked up at this time because current is flowing through its upper winding in opposition to that in its lower winding over a circuit which extends from 45 (+), resistance unit RS, back contact 4 of button 1SB, back contact 8 of button 2SB, front contact 16 of button 3SB, front contact 64 of relay 3CH¹, back contact 65 and upper winding of relay 1SD to (-). Since the value of resistance unit RS is approximately the same as the value of the lower winding of relay 3CH¹, the current flow through the two windings of relay 1SD is approximately equal and since these two windings are differentially connected the relay 50 is not actuated.

When the operator restores button 3SB to normal, however, relay 1SD is actuated by means of the current flowing through its lower winding alone, due to the fact that the current through its upper winding is interrupted when front contact 16 of button 3SB is opened. The actuation of relay 1SD opens the circuit through its upper winding at back contact 65 so that the upper winding will not receive current upon another actuation of button 3SB. At this time, 55 relays 3CH¹ and 1SD are stuck up by current flowing through their lower windings in series.

When button 1SB is actuated the only CH relay which gets current is relay 1CH², since the

(-) potential as selected by contacts 10, 11 and 12 of the sequence determining relays is now connected to the upper winding of only relay 1CH² of this series. Relay 1CH² is picked up over a circuit extending from (+) front contact 5 2 of button 1SB, upper winding of relay 1CH², front contact 10 of relay 1SD, back contact 11 of relay 2SD, and back contact 12 of relay 3SD to (-). Relay 1CH² closes a stick circuit for itself extending from (+), front contact 13 and 10 lower winding of relay 1CH² and the lower winding of relay 2SD to (-).

Relay 2SD is not picked up at this time because of the current flowing through its upper winding which is equal and opposite to that through its lower winding. This circuit extends from (+), resistance unit RS, front contact 4 of button 1SB, front contact 14 of relay 1CH², back contact 15 of relay 2SD, and the upper winding of relay 2SD to (-). When button 1SB is restored to normal the current through the upper winding of relay 2SD is interrupted at front contact 4 of button 1SB, which allows this relay to be actuated by means of the current flowing through its lower winding alone. 20 Relays 1CH² and 2SD are now energized through the lower windings in series.

When button 2SB is actuated the only relay in the second series which gets current is relay 2CH³. The circuit for picking up relay 2CH³ 30 extends from (+), back contact 1 of button 1SB, front contact 5 of button 2SB, upper winding of relay 2CH³, front contact 11 of relay 2SD and back contact 12 of relay 3SD to (-). Relay 2CH³ closes a stick circuit for itself extending from 35 (+), front contact 16 and lower winding of relay 2CH³ and the lower winding of relay 3SD to (-). Relay 3SD is not picked up at this time, because of an equal and opposite effect in its upper winding due to current flowing over a 40 circuit extending from (+), resistance unit RS, back contact 4 of button 1SB, front contact 8 of button 2SB, front contact 17 of relay 2CH³, back contact 18 and upper winding of relay 3SD to (-). When button 2SB is restored to normal 45 the circuit through the upper winding of relay 3SD is interrupted at front contact 8 of button 2SB so that relay 3SD is actuated by means of the current which flows through its lower winding alone. Relays 2CH³ and 3SD are now energized through their lower windings in series. 50

Polarity selection and transmission

The communication system is initiated from the control office when any change relay is 55 picked up. The picking up of a change relay is effective to pick up a common change repeating relay (not shown) which in turn picks up the control cycle relay C to mark this cycle as one for the transmission of controls. Since this particular part of the operation of the system is immaterial to an understanding of the present invention, and since the system may be initiated in any desired manner, these detailed circuits have been omitted. One example of the manner in which the system may be initiated into a cycle of operations, as a result of one or more change relays being picked up, is disclosed in the above-mentioned prior application Ser. No. 640,062. 60

70 It will be recalled that in the assumed example, relays 3CH¹, 1CH² and 2CH³ were picked up in the order named and stuck up. Also, relays 1SD, 2SD and 3SD were picked up in the order named and stuck up. 75

- The only code determining relay which can be picked up, at this time, is relay 3CD picked up over a circuit extending from (+), front contact 66 of relay 1SD, front contact 38 of relay 3CH¹ and winding of relay 3CD to (-). Although all three sequence determining relays are picked up at this time, the energizing circuits for the other code determining relays are interrupted at back contact 66 of relay 1SD.
- 10 The impulses placed upon the line circuit for the succeeding cycle of operations are of polarities determined in accordance with the positions of the code jumpers and the control levers rendered effective by the picking up of relay 3CD.
- 15 As soon as relay 3CD is picked up following the energization of relay C, one or the other of the polarity control relays PC and NC is energized depending upon the position of the first code jumper.
- 20 More specifically, if code jumper 20 is in the position illustrated, relay NC is energized, but if this code jumper is in its dotted line position, relay PC is energized. For example, assuming code jumper 20 to be in the position illustrated, 25 the circuit for energizing relay NC extends from (+), front contact 41 of relay C, back contacts 42, 43 and 44 of relays 3V, 2V and 1V, respectively, front contact 21 of relay 3CD, code jumper 20, negative bus 48 and winding of relay 30 NC to (-).
- 30 The energization of relay NC applies a negative impulse to the control line circuit including conductors 10 and 12. It is apparent, that code jumper 20, in its alternate or dotted line position, 35 causes the energization of relay PC which applies a positive impulse to the line circuit. Assuming, that relay PC is energized, the control line is energized from the positive terminal of battery CB over a circuit including back contact 50 of 40 relay NC, front contact 51 of relay PC, back contact 52 of relay EP, winding of line relay F, control line wire 10, and through the various field station line relays in series to the return conductor 12, and thence through front contact 45 53 of relay PC and back contact 54 of relay NC to the negative terminal of battery CB.
- 45 In the event that relay NC is energized, then contacts 50 and 54 of this relay reverse the connection from battery CB to the line circuit 50 so that an impulse of negative polarity is applied to line conductor 10. The energization of line relay F and the subsequent deenergization of the control line circuit by relay EP, results in the picking up of stepping relay 1V, all in 55 a manner explained in the above-mentioned prior application.
- 60 One or the other of the polarity control relays PC and NC will now be energized, as determined by the position of code jumper 30. Assuming jumper 30 to be connected as illustrated in Fig. 2, relay NC is energized over a circuit extending from (+), front contact 41 of relay C, back contacts 42 and 43 of relays 3V and 2V, respectively, front contact 44 of relay 1V, front contact 22 of relay 3CD, code jumper 30, negative bus 48 and winding of relay NC to (-).
- 65 When the system takes its next step, a circuit is completed for energizing relay PC, which extends from (+), front contact 41 of relay C, back contact 42 of relay 3V, front contact 43 of relay 2V, front contact 23 of relay 3CD, code jumper 31, positive bus 47 and winding of relay PC to (-). It will be obvious that the jumpers 20, 30 and 31 connected as shown cause a code of (-), (-), (+) to be applied to the line for

selecting the station corresponding to this code and associated with relay 3CD.

When the system takes its next step by picking up relay 3V, either relay PC or NC is energized over a circuit extending from (+), through front contact 41 of relay C, front contact 42 of relay 3V, and front contact 32 of relay 3CD to positive code bus 47 or negative bus 48, as selected by control lever 2SML which is associated with contact 32 of relay 3CD.

At the end of this cycle of operations, relay SA is dropped which deenergizes the winding of relay 2SA by the dropping of front contact 33. During the interval between the dropping of relay SA and the dropping of relay 2SA, a circuit is effective to deenergize relay 3CH and to maintain relay 1SD energized. This circuit extends from (+), back contact 33 of relay SA, front contact 34 of relay 2SA, conductor 35, front contact 36 of relay 1SD to the right-hand terminal of the lower winding of relay 3CH¹. Since the left-hand terminal of this winding is connected to (+) by way of front contact 63 of relay 3CH¹, and since the upper winding of this relay is open, the effect of short circuiting the lower winding causes its release. This circuit from (+), at back contact 33 of relay SA also extends through the lower winding of relay 1SD to (-), and since the upper winding of this relay is deenergized at this time, it remains in its actuated position.

When relay 2SA drops its front contact 34, conductor 35 is deenergized, which deenergizes the lower winding of relay 1SD allowing this relay to drop its contacts. Another cycle will be immediately started because it has been assumed that relay 1CH² is picked up. This cycle will be effective to select station 1 as determined by relay 1CD being picked up over a circuit extending from (+), back contact 66 of relay 1SD, front contact 69 of relay 2SD, front contact 79 of relay 1CH², and winding of relay 1CD to (-).

During this cycle, relays PC and NC are selectively conditioned to apply the code combination (+), (+), (-) to the line circuit as determined by the combination of code jumpers 40, 55 and 58. Likewise, during this cycle, the control devices at the selected station will be conditioned in accordance with the selection of relays PC and NC as determined by the positions of the control levers, such as lever 1SML selectively associated with front contact 42 of relay 3V by front contact 62 of relay 1CD.

At the end of this cycle of operations the momentary impulse applied to conductor 35 by the dropping of contact 33 of relay SA maintains relay 2SD energized over the circuit extending from conductor 35, back contact 36 of relay 1SD, front contact 37 of relay 2SD and lower winding of relay 2SD to (-). This circuit also extends to the right-hand terminal of the lower winding of relay 1CH² and since the left-hand terminal of this winding is connected to (+) at front contact 73 of this relay, it is short circuited causing the release of the relay. When relay 2SA drops its front contact 34, conductor 35 is deenergized which deenergizes the lower winding of relay 2SD allowing it to drop its contacts.

The third cycle of operations is initiated because there is still another change relay picked up (relay 2CH³), which is effective to select station No. 2 as determined by relay 2CD being energized. Relay 2CD is picked up over a circuit extending from (+), back contact 66 of relay 75

1SD, back contact 69 of relay 2SD, front contact 49 of relay 3SD, front contact 39 of relay 2CH³ and winding of relay 2CD to (—).

5 Station 2 with code call (—), (+), (—) is selected as determined by the polarity of the impulses applied to the line circuit by relays PC and NC. These relays are selectively picked up as determined by the positions of code jumpers 24, 10 25 and 26 selected in rotation by way of front contacts 27, 28 and 29 of relay 2CD by the selective operation of the stepping relays. The particular controlling devices at the selected station are governed in accordance with the lever positions as selected by additional contacts of 15 relay 2CD, such as front contact 13 which selects lever 2SML.

At the end of this cycle of operations the momentary application of (+) potential to conductor 35 maintains relay 3SD energized over 20 the circuit extending through back contacts 36 and 37 of relays 1SD and 2SD, respectively, and front contact 38 of relay 3SD to (—) through the lower winding of this relay. This (+) impulse is also applied to the right-hand terminal 25 of the lower winding of relay 2CH³ and since this relay has (+) potential connected to the left-hand terminal of this winding through its front contact 76, the winding is short circuited and the relay is dropped. When relay 2SA drops its 30 front contact 34, conductor 35 is deenergized which deenergizes the lower winding of relay 3SD allowing it to drop its contacts.

It is believed that the above examples are sufficient to indicate the manner in which the 35 stations are selected in the exact order of operation of the starting buttons. It is obvious that if the starting buttons 1SB, 2SB and 3SB are operated in the order 3, 2, 1, then relays 3CH¹, 2CH² and 1CH³ are picked up. This effects the 40 picking up of relays 3CD, 2CD and 1CD, one at a time, in rotation, as the cycles are marked off by the operation of the sequence determining relays.

In the event that button 1SB is actuated three 45 times in rapid succession, then relays 1CH¹, 1CH² and 1CH³ will be successively picked up, being selected in rotation by contacts 70 and 71 of relays 1SD and 2SD. In this event relay 1CD is picked up for all three cycles so that the station associated with this code determining relay 50 is selected three times in rotation.

It will be apparent that the code jumpers can be connected in any desired order for obtaining the required combinations of (+) and (—) impulses in the control line circuit. It will also be obvious that additional code jumpers may selectively connect the PC and NC relays to the stepping relay bank selective circuit by means of additional contacts on the CD relays when the size of the system requires these additional jumpers. It will also be apparent that the present invention may be applied to a communication system of the single circuit two-wire type in which controls and indications are transmitted over the same line circuit, instead of being applied to the system disclosed in the above-mentioned prior application Ser. No. 640,062, which relates to the use of separate line circuits for the transmission of controls and indications. 65

70 Having thus described a centralized traffic controlling system as one specific embodiment of the present invention, it is desired to be understood that this form is selected to facilitate in the disclosure of the invention rather than to limit the number of forms which it may assume, 75

and it is to be further understood that various modifications, adaptations and alterations may be applied to the specific form shown to meet the requirements of practice without in any manner departing from the spirit or scope of the present invention except as limited by the appended claims.

What I claim is:—

1. In combination, a circuit, a plurality of keys, a plurality of code determining relays corresponding to said keys, a plurality of groups of storing relays corresponding to said keys, means responsive to the consecutive actuations of said keys for consecutively operating storing relays in the groups corresponding to the actuated keys, circuit means controlled by said storing relays for selecting said code determining relays, a step-by-step device operating through a cycle in response to the operation of any code determining relay, means controlled by 10 said step-by-step device for transmitting a distinctive code to said circuit in accordance with the particular code determining relay which is operated, means for operating said code determining relays between cycles of said step-by-step device in the order of location of the operated storing relay in the associated group, and means for selecting the particular storing relay in the group associated with the actuated key in accordance with the sequential order in 15 which said key is actuated.

2. In combination, a circuit, a plurality of keys, a plurality of code determining relays corresponding to said keys, a plurality of groups of storing relays corresponding to said keys, 20 a plurality of sequence determining relays corresponding to the number of storing relays in each group, means responsive to the consecutive actuations of said keys for consecutively operating storing relays in the groups corresponding to the actuated keys, circuit means controlled by 25 said storing relays for selecting said code determining relays, a step-by-step device operating through a cycle in response to the operation of any code determining relay, means controlled by 30 said step-by-step device for transmitting a distinctive code to said circuit in accordance with the particular code determining relay which is operated, means for operating said code determining relays between cycles of said step-by-step device in the order of location of the operated storing relay in the associated group, and means for selecting the particular storing relay in the group associated with the actuated key in accordance with the sequential order in 35 which said key is actuated.

3. In a transmitter, the combination with a code transmitting means for sequentially transmitting a plurality of series of coded impulses 40 in the same sequential order in which a plurality of manually operable devices are operated, code determining relays for coding said impulses one relay for each of said series, one manually operable device for each of said relays, means effecting the energization of said relays by said devices in the sequential order in which said devices are successively operated independent of the length of time elapsing between successive operations of said devices, and means for 45 preventing the energization of more than one of said relays at any one time.

4. In a code transmitter, the combination with a plurality of control levers, a starting button for each lever, a relay controlled by 50

each button, means for permitting energization of only one of said relays at any one time, means controlled by any one of a plurality of orders of operation of said buttons and irrespective of the time intervals between for always predetermining a corresponding order of operation of said relays, and means governed by each of said relays for rendering the control lever of the corresponding button effective to distinctively operate said transmitter.

5. In a code transmitter, the combination with a plurality of control levers, a starting button for each lever, a relay controlled by each button, means for permitting energization of only one of said relays at any one time, means controlled by any one of a plurality of orders of operation of said buttons and irrespective of the time intervals between for always predetermining a corresponding order of operation of said relays, means governed by each of said relays for rendering the control lever of the corresponding button effective to distinctively operate said transmitter, and means for storing the actuations of said plurality of buttons.

25. 6. In a code transmitter, a circuit to which codes are applied, means for operating said transmitter through a cycle, a plurality of starting buttons, code determining means rendered active in response to an actuation of any one 30 of said buttons for applying a distinctive code to said circuit during said cycle in accordance with the particular button actuated, means controlled by a plurality of subsequent actuations of said button before the end of said cycle for 35 subsequently and successively applying said distinctive code to said circuit once for each of said subsequent actuations, and means controlled by the actuation of any other of said buttons following said subsequent actuations for 40 preventing the operation of any other code determining means as long as said first code determining means remains active.

7. In a code transmitter, a circuit to which different series of coded impulses are applied, 45 a plurality of code determining relays for controlling the application of said series of impulses to said circuit, a starting button individual to each of said code determining relays, a plurality of storing relays, a plurality of sequence 50 determining relays, means responsive to the sequential operation of said buttons in variable order for sequentially operating said sequence determining relays in an invariable order, means responsive to the sequential operation of said 55 buttons in variable order for sequentially operating said storing relays in corresponding variable order, means controlled by said sequence determining relays for predetermining the order of operation of said code determining relays, 60 and means controlled by said storing relays for selecting said code determining relays.

8. In a code transmitter; a plurality of keys; a plurality of code determining relays, one for each key; means including a chain of sequence 65 determining relays operated in response to consecutive operations of said keys for causing said code determining relays to control the transmission of codes corresponding to the operated keys; means controlled by said keys for determining that said sequence determining relays shall always be operated in a definite rotation to determine a definite rotation in the transmission of said codes; a release circuit controlled by consecutive operations of said transmitter; and 70 means responsive to the consecutive control of

said release circuit for restoring the operated sequence determining relays in the rotation in which they were operated.

9. In a code transmitter; a plurality of code determining relays each controlling the transmission of a distinctive code; a storage relay group associated with each of said code determining relays; a plurality of keys; a chain of sequence determining relays for connecting said keys to said storage relays sequentially, the storage relays of the groups to which the keys are connected being responsive to the operation of the associated key for operating one of said code determining relays and operating said sequence determining relays to connect said keys to the next storage relay group in sequence; a release circuit controlled by consecutive operations of said transmitter; and means controlled by said release circuit for releasing the operated storage relays and the operated sequence determining relays in the order in which they were operated.

10. In combination; a plurality of manually operable keys; a plurality of groups of double wound storing relays, one group for each key; a double wound sequence determining relay for each key; pick up circuits for said storing relays controlled by said sequence determining relays; means responsive to a first actuation of any one of said keys for picking up the first storing relay in the associated group by energizing its pick up winding; means for sticking said first storing relay by energizing its stick winding in series with a first winding of the associated sequence determining relay, said associated sequence determining relay being prevented from picking up by the actuated key energizing its second winding; means responsive to the release of the actuated key for effecting the picking up of said sequence determining relay by deenergizing its second winding; and means controlled by the picking up of said sequence determining relay for switching the circuits of said keys to the second sequence determining relay and the second storing relay in each group.

11. In combination; a plurality of manually operable keys; a plurality of groups of double wound storing relays, one group for each key; a double wound sequence determining relay for each key; pick up circuits for said storing relays controlled by said sequence determining relays; means responsive to a first actuation of any one of said keys for picking up the first storing relay in the associated group by energizing its pick up winding; means for sticking said first storing relay by energizing its stick winding in series with a first winding of the associated sequence determining relay, said associated sequence determining relay being prevented from picking up by the actuated key energizing its second winding; means responsive to the release of the actuated key for effecting the picking up of said sequence determining relay by deenergizing its second winding; and means controlled by the picking up of said sequence determining relay for switching the circuits of said keys to the second sequence determining relay and the second storing relay in each group, and means for releasing the sequence determining relays in the order of their operation.

12. In combination; a plurality of manually operable keys; a plurality of groups of double wound storing relays, one group for each key; a double wound sequence determining relay for each key; pick up circuits for said storing relays controlled by said sequence determining relays;

means responsive to a first actuation of any one of said keys for picking up the first storing relay in the associated group by energizing its pick up winding; means for sticking said first storing relay by energizing its stick winding in series with a first winding of the associated sequence determining relay, said associated sequence determining relay being prevented from picking up by the actuated key energizing its second winding; means responsive to the release of the actuated key for effecting the picking up of said sequence determining relay by deenergizing its second winding; means controlled by the picking up of said sequence determining relay for switching the circuits of said keys to the second sequence determining relay and the second storing relay in each group, means for releasing the sequence determining relays in the order of their operation; and a plurality of code determining relays individually selected and energized by the picked up storing and sequence determining relays.

13. In a code transmitter, a plurality of code determining relays, means including each of said code determining relays for controlling the transmission of a series of combinations of coded impulses, a starting button individual to each of

said code determining relays, a plurality of sequence determining relays, and means including said buttons and said sequence determining relays for effecting the distinctive control of said code determining relays in any one of a plurality of distinctive sequences of operations in response to the total possible sequences of operations of said buttons independent of the time intervals elapsing between successive operations of said buttons. 10

14. In a code transmitter, a plurality of code determining relays, means including each of said code determining relays for controlling the transmission of a series of combinations of coded impulses, a starting button individual to each of said code determining relays, a plurality of sequence determining relays, and means including said buttons and said sequence determining relays for effecting the control of said code determining relays in any one of a plurality of distinctive sequences of operations in response to a corresponding plurality of sequences of operations of said buttons independent of the time interval elapsing between successive operations of said buttons. 15 20 25
